E. G. ROWLEY,
COOKING VESSEL,
APPLICATION FILED DEC. 8, 1920.

1,406,159.

Patented Feb. 7, 1922.

Inventor
Edward G. Rowley
By his Attorney Frank C. Fischer

UNITED STATES PATENT OFFICE.

EDWARD G. ROWLEY, OF NEWARK, NEW JERSEY, ASSIGNOR OF ONE-HALF TO SUN TYPEWRITER COMPANY, OF NEWARK, NEW JERSEY, A CORPORATION OF NEW JERSEY.

COOKING VESSEL.

1,406,159.

Specification of Letters Patent. Patented Feb. 7, 1922.

Application filed December 8, 1920. Serial No. 429,056.

To all whom it may concern:

Be it known that I, EDWARD G. ROWLEY, a citizen of the United States, residing in Newark, in the county of Essex and State of New Jersey, have invented certain new and useful Improvements in Cooking Vessels, of which the following is a specification.

This invention relates to improvements in portable boilers, such as are used for domestic and other purposes where it is required to raise the temperature of a liquid by the application of heat at the bottom, the main object being to provide a boiler in which the liquid contained therein is heated far more rapidly than in a boiler of the usual construction exposed to the same heat.

A further object is to conserve the heat as fully as possible, directing it upon the boiler heating elements, the same being arranged to cause a lively circulation of the liquid within the boiler directly upon heat being applied.

These objects are attained by the novel construction, combination and arrangement of parts hereinafter described and shown in the accompanying drawings, forming a material part of this disclosure, and in which:

Figure 1 is a partial side elevational, partial vertical sectional view of a boiler, made in accordance with the invention.

Figure 2 is a fragmentary bottom plan view thereof.

Figure 3 is a similar fragmentary view looking from the top of the same.

It is a well known fact that a vessel having a substantially flat bottom and cylindrical or flaring side walls will when placed over a heat source, cause the liquid, as water, within it to boil due to the heat imparted to it, the water, when in a state of ebullition, showing minute bubbles of steam rising from the bottom and inward from the sides, the water moving towards the center of the vessel in eddying currents caused by the slight difference in temperature.

In the present invention the water moves oppositely or outwardly from the center, which is raised in a geyser like manner due to the peculiarities of the structure.

Referring to the drawings in detail, the numeral 10 designates the walls of a vessel, here shown to be cylindrical, although the shape is inconsequential, the body being provided with handles 11 secured in any pre-

ferred manner and obviously a cover (not shown) may be supplied.

A bottom 12 is raised from the extreme lower edge of the walls, this bottom being secured by an internal flange 13 as shown or other approved method whereby a tight and effective joint is obtained, the bottom being preferably level and smooth upon its inner surface.

Formed through the bottom 12 are a plurality of circular openings 14 in which are secured the ends of relatively small tubes 15, preferably made of copper, bent into looped formation and rigidly fastened by spot welding, hard soldering or like means not readily affected by continuous or intermittent subjections to heat.

These tubes are arranged preferably in series of rows, at more or less distance from the center relatively uniformly spaced and in radial relation, the bight of the bent tubes 75 clearing the plane of the vessel's bottom edge.

In operation, the vessel having been partially filled with the liquid to be boiled, is placed over any common form of heater, as 80 a gas burner, the flames of which, when ignited are concentrated by the guard like flange 13 and wall of the vessel, so that substantially all of the heat emanations are directed upon the tubes 15, which as will be 85 understood, are filled with the liquid.

This results in an almost immediate boiling effect as the small quantity of liquid in each tube is surrounded by intense heat, causing it to form steam at once which passes 90 up through the body of liquid in the vessel heating the same in an unusually rapid manner.

It is found that the liquid when the device is in full operation, tends to form a cone or 95 geyser like appearance, being hotter at the center than the edges and that the liquid is maintained in active circulation so long as heat is applied.

Thus the effective heating area of the bottom is not only very considerably increased by the added area of the tubes, but the liquid is brought as nearly as may be into contact with the flames.

From the foregoing it will be seen and 105 understood that a material improvement in vessels of this class has been disclosed and, while a preferred embodiment has been

shown, it is possible to make minor changes in construction without departing from the spirit of the invention.

Having thus described my invention, what I claim as new and desire to secure by Letters Patent, is:—

1. A heating vessel comprising a hollow body having a tight bottom, a depending guard element circumadjacent the bottom and forming with said bottom a heating chamber and radially disposed tubular loops fixed at their ends in said bottom and disposed in said chamber whereby the exposed heat area of the bottom is increased.
- 15 2. A heating vessel comprising a hollow

body having a bottom, the walls of said body extending therebelow and forming with said bottom a heating chamber, and a plurality of radially disposed tubular loops having their open ends engaged in said bottom, said loops being subjected to heat on their exteriors, the bights of said loops being above the plane of said walls closely adjacent the heat source.

This specification signed and witnessed this seventh day of December, 1920.

EDWARD G. ROWLEY.
